MAGNETIC TAPE UNIT OR SIMILAR ARTICLE

Guy S. Fugit, Levittown, N.Y., assignor to Potter Instrument Company, Inc., Plainview, N.Y., a corporation of New York

Filed Apr. 16, 1964, Ser. No. 79,529

Term of patent 14 years

(Cl. D26—5)

In the drawings:

The single figure showing my design depicts a perspective view of the front panel of a magnetic tape unit or similar article.

The side, top and back of the unit are conventional. The dominant features of my design reside in those portions shown in full lines on the drawing.

I claim:

The ornamental design for a magnetic tape unit or similar article, as shown and described.
